UNITED STATES PATENT OFFICE

2,208,871

DOOR OF STOVES AND RANGES

Walter F. Rogers, Oak Park, Ill., assignor to
 Crown Stove Works, Cicero, Ill., a corporation
 of Illinois

Application July 14, 1939, Serial No. 284,467

4 Claims. (Cl. 126—194)

This invention relates to the oven doors of stoves and ranges and means for hinging said doors to the lower edge of the oven opening, and among the objects of the invention are; to provide a hinge construction wherein practically all of the hinge elements are concealed, to provide a hinge construction which will permit the door to be readily applied to and removed from the stove body by the mere manipulation of a pair of hinge pintle latches and without requiring the removal of the pintle or any other hinge elements, to provide a hinge construction that will avoid any chafing or marring of the enamel of the stove front in the region of the hinge, to provide an improved spring-actuated device for supporting the door in fully lowered or open position and assisting the closing movement, and to provide a hinge construction especially well adapted for use on double-walled insulated doors.

An illustrative embodiment of the invention is shown in the accompanying drawing, in which—

Fig. 1 is a perspective view of a lower corner portion of the oven opening and door, showing the latter in fully lowered or open position.

Fig. 2 is a perspective view of the cooperating hinge members carried by the door frame and door, showing the locking latch at one end engaged with its hinge pintle and the locking latch at the other end disengaged from its hinge pintle.

Fig. 3 is a vertical section taken on the line 3—3 of Fig. 1.

Fig. 4 is a vertical section taken on the line 4—4 of Fig. 3.

Fig. 5 is a view similar to Fig. 3, but showing the door in fully closed position.

In the drawing 10 designates the lower horizontal member and 11 one of the vertical side members of an oven door frame, these frame members being preferably of the inwardly facing channel form indicated in the drawing. Secured in and forming in effect a part of the frame member 10 is a bar 12 having on its ends forwardly projecting brackets 13 formed with horizontal slots 14 open at their forward ends, these brackets forming fixed leaves of the oven door hinge structure. 15 designates as an entirety the oven door which, in the form herein shown, is a heat insulated door comprising spaced outer and inner walls 16 and 17 lapped at their edges and enclosing a filling 18 of heat insulating material. The two walls of the door are bonded together by any suitable means such as screw bolts 19 passed through washers 20 on the inner wall 17 that seat the heads of the bolts and loops 21

soldered or spot welded to the inner side of the wall 16.

Mounted in the side edges of the door between the walls 16 and 17 are a pair of box-like hinge leaves 22 that constitute the movable leaves of the oven door hinge structure. Mounted in and extending between the side walls of said hinge leaves (see Fig. 4) are hinge pintles 23, which are adapted to enter and seat in the slots 14 of the bracket 13. The pintles 23 are removably locked in the slots 14 by latches 24 pivoted at 25 on the brackets 13 and having on their forward ends curved depending fingers 26 that hook over the pintles 23, as clearly shown in Fig. 4. The inner wall 17 of the door has slots 27 and the top walls of the hinge leaves 22 have slots 28 registering with the slots 27 that permit the brackets and latches to enter the lower edge portion of the door and engage with the pintles 23.

The channel frame members, such as 10 and 11, are usually of porcelain, and the brackets 13 and latches 24 project from the bar 12 through vertical slots 29 (Fig. 1) in the horizontal frame member 10; and the hinge pintles 23 are spaced a greater distance from the frame member 10 than from the lower edge of the door, as shown in Fig. 3, as a result of which there is no chafing or rubbing of the lower edge of the door on the door frame such as might otherwise wear the finish of the latter.

Springs of various sorts are commonly used to retard the opening movement, and assist the closing movement of oven doors. In my present invention I combine a spring having this function with means for limiting the door opening movement to a substantially horizontal position of the door. Describing this mechanism, 30 designates a pin mounted in and extending between the side walls of each hinge leaf 22 in rear of the hinge pintle 23. 31 designates a flat link, preferably of the form shown in Fig. 1, that is slideable through a vertical guide slot 32 in the lower end of the side frame member 11 along the side wall of the oven. On the forward end of link 31 is a depending hook 33 that enters through a slot 34 in the wall 17 and a registering slot 35 in the outer longitudinal corner of the leaf 22 to engage with the pin 30, as shown in Fig. 3. To the rear end of the link 31 is attached a rod 36 disposed on the outer side of the side wall of the oven and connected at its rear end to the upper end of a lever 37 that is pivoted at 38 to the side wall of the oven. To the lower end of lever 37 is connected a strong pull spring 39 that is anchored to a bracket 40 on the side

wall of the oven and cushions the opening movement and assists the closing movement of the door. On the link 31 is a vertical stop shoulder 41 that, in the fully lowered position of the door, contacts with the portion of the frame member 11 just above the slot 32 and holds the door in substantially horizontal position.

An important advantage of the described structure is the ease of application and removal of the door. To apply the door it is necessary only to raise the latches 24, enter the hinge pintles 23 in the bracket slots 14, lower the latches, and then pull forward the links 31 and engage their hooks 33 with the pins 30. To remove the door, 10 it is necessary only to disengage the hooks 33 from the pins 30, raise the latches 24, and then withdraw the door from the stove body.

Variations and modifications in the details of structure and arrangement may be made within 15 the scope and coverage of the claims.

I claim:

1. In a stove, the combination with an oven door frame and a door having spaced outer and inner walls, of means for removably hinging said door at its lower edge to the lower horizontal member of the frame comprising forwardly projecting brackets on said lower frame member having slots open at their forward ends, box-like hinge leaves mounted in the side edges of said door between said walls; hinge pintles mounted in and extending between the side walls of said leaves and adapted to enter and seat in said slots, and latches pivotally connected to said lower frame member adapted to engage with said pintles and lock the latter in said slots; said door and hinge leaves having suitably located slots to permit said brackets and latches to engage with said pintles.

2. In a stove, the combination with an oven door frame and a door having spaced outer and inner walls, of means for removably hinging said door at its lower edge to the lower horizontal

member of the frame comprising forwardly projecting brackets on said lower frame member having slots open at their forward ends, box-like hinge leaves mounted in the side edges of said door between said walls, hinge pintles mounted in and extending between the side walls of said leaves and adapted to enter and seat in said slots, and latches pivotally connected to said lower frame member adapted to engage with said pintles and lock the latter in said slots; the inner and lower edge walls of said door and the top walls of said hinge leaves having suitably located slots to permit the entrance of said brackets and latches into engagement with said pintles.

3. In combination with the subject-matter defined in claim 1, pins mounted in and between the side walls of the hinge leaves in rear of the hinge pintles, links mounted to slide inwardly and outwardly along the side walls of the oven and having on their forward end hooks removably engaged with said pins, and springs exerting an inward pull on said links; said door and hinge leaves having suitably located slots to permit said hooks to be engaged with and disengaged from said pins.

4. In combination with the subject-matter defined in claim 1; pins mounted in and between the side walls of the hinge leaves in rear of the hinge pintles, links mounted to slide inwardly and outwardly along the side walls of the oven and having on their forward ends depending hooks removably engaged with said pins, pull springs anchored to the side walls of the oven and exerting an inward pull on said links, and stops on said links serving through contact with the door frame to limit the down swing of the door to a substantially horizontal position; said door and hinge leaves having suitably located slots to permit said hooks to be engaged with and disengaged from said pins.

WALTER F. ROGERS.
